UNITED STATES PATENT OFFICE

156,726

BEVERAGE HEATING APPLIANCE

Gilbert C. Gettelman, Hartford, Wis.

Application October 27, 1948, Serial No. 149,324

Term of patent 14 years

(Cl. D81—10)

To all whom it may concern:

Be it known that I, Gilbert C. Gettelman, a citizen of the United States, residing at Hartford, in the county of Washington and State of Wisconsin, have invented a new, original, and ornamental Design for a Beverage Heating Appliance, of which the following is a specification, reference being had to the accompanying drawing, forming part thereof.

In the drawing:

Fig. 1 is a top view of a beverage heating appliance, showing my new design;

Fig. 2 is a front elevational view thereof; and
Fig. 3 is a side elevational view.

The dominant features of my design are shown in full lines.

I claim:

The ornamental design for a beverage heating appliance, substantially as shown and described.

GILBERT C. GETTELMAN.
